FURNACE

Filed Sept. 29, 1927

UNITED STATES PATENT OFFICE

FRED H. DANIELS, OF WORCESTER, MASSACHUSETTS, ASSIGNOR TO RILEY STOKER CORPORATION, OF WORCESTER, MASSACHUSETTS, A CORPORATION OF MASSACHUSETTS

FURNACE

Application filed September 29, 1927. Serial No. 222,792.

This invention relates to furnaces, and is particularly applicable to a furnace provided with an automatic stoker mechanism arranged to transport fuel progressively therethrough for combustion.

tremely high ratings, and this lowering of the efficiency causes the fuel consumption to be unnecessarily high and is obviously undesirable.

It is accordingly a further object of my invention to provide a furnace which can be successfully operated at high rates of combustion without materially lowering the efficiency. 55

With these and other objects in view, as will be apparent to those skilled in the art, my invention resides in the combination of parts set forth in the specification and covered by the claims appended hereto. 60

In accordance with my invention I provide a stoker constructed for transporting a bed of fuel progressively from the front wall of a furnace toward an ash dump within the furnace and preferably adjacent to the rear wall thereof. In order to make up for the deficiency in combustible gases adjacent the ash dump I introduce fuel in pulverized form into the combustion chamber and preferably directly thru the rear wall of the furnace. 65 It is desirable that this pulverized fuel be introduced by a burner of the so-called turbulent type which is adapted to produce a rapid and thorough mixture of gases in the furnace, ensuring the desired efficiency of combustion. 70

Referring to the drawing in which like reference numerals indicate like parts, 75

Fig. 1 is a longitudinal section thru a furnace embodying my invention;

Fig. 2 is a section on the line 2--2 of Fig. 80 1, with certain parts broken away; and

Fig. 3 is a section on the line 3--3 of Fig. 1, with parts broken away. 85

The embodiment of my invention illustrated in the drawing comprises a combustion chamber 10 provided with a front wall 11 and a rear wall 12 formed of suitable refractory material. A horizontal water tube boiler 15 of well-known construction may be mounted above the chamber 10 and arranged to absorb heat from the gases issuing therefrom. In the drawing, I have illustrated somewhat diagrammatically a stoker of the multiple retort underfeed type. Such stokers are well-known to those skilled in this art and are described, for example, in the U. S. 90 95 100

10 dump adjacent to the rear wall of the furnace. Combustion conditions in the front part of such a furnace adjacent to the point of entrance of the fuel are very different from the conditions in the rear part of the furnace. The fuel on entering the furnace gives off its volatile matter, and the fuel bed being relatively thick at this point there is likely to be a deficiency of air supplied therethrough, which results in the escape of a 15 large amount of rich gas from this part of the fuel bed. In the rear part of the furnace, on the other hand, the fuel bed is relatively thin and consists largely of ash and refuse, and in order to avoid the losses caused by the presence of combustible matter in this refuse it is necessary to supply air therethrough and this usually gives an excess of air in the furnace at this point. It is obvious that this stratification of gases is the cause 20 of material reduction in efficiency, as the rich and lean gases pass into the boiler tubes unmixed and are there cooled below the point of ignition so that further combustion becomes impossible. 25

30 It is, accordingly, one object of this invention to provide a stoker in which a bed of fuel is moved progressively toward an ash dump at the rear and in which the losses caused by stratification of the gases shall be reduced to the minimum.

In modern power plants and particularly those engaged in supplying power to municipalities, the load demand on the furnaces varies considerably at certain times of the day, and it is frequently necessary to operate the furnaces at extremely high ratings when these so-called peak loads occur. It has been found that with the usual type of automatic stoker the efficiency becomes very much lower when the machine is operated at these ex-

patents to Riley No. 1,322,822 and Riley et al No. 1,605,665. The stoker illustrated comprises a fuel hopper 16 mounted adjacent to the front wall 11 on the outside thereof. In 5 front of each retort of the stoker and beneath the hopper 16 is a ram 18 arranged to be reciprocated by a suitable crankshaft 19 which is joined thereto by a connecting rod 20. The crankshaft 19 is rotated slowly by means of 10 a suitable source of power connected to a gear reduction mechanism contained in the gear box 22. It will be understood that the retorts are trough shaped structures extending rearwardly in parallel relation to each 15 other from the front wall 11. Each retort has a bottom 24 and side walls 25, the latter being surmounted by suitable tuyère blocks 27 arranged to support the fuel bed and admit air thereto. In the rear of the retorts I have 20 illustrated an overfeed grate section 30 and an overfeed rocker apron 31. The air to the overfeed grate and the rocker apron is controlled by suitable dampers 33 and 34 respectively. 25 In order to supply forced draft to the stoker, the space beneath the retorts is enclosed to form an air chamber 38. The bottom 39 of this chamber is arranged to slope downwardly as illustrated so that the fine fuel which 30 sifts thru the grate surface may be easily removed by opening the slide gate 40. A suitable fan 42 is arranged to deliver air under pressure into the air chamber 38 thru an air duct 43 provided with a regulating damper 35 45.

As a suitable means for disposing of the ash and refuse from the stoker, I have illustrated a double roll clinker grinder 48 extending transversely of the chamber 10 between the rocker apron 31 and the rear wall 12. These rolls are preferably constructed as shown in the U. S. patent to Riley No. 1,441,027, and are arranged to grind the ash against adjustable apron plates 50. The refuse after being ground by the rolls falls into the ash pit 53 which may be of any desired construction.

During operation the contour of the fuel bed in a stoker of this type will be somewhat 53 as shown by the dot and dash line 55. It is to be noted that such a fuel bed is much thicker near the front of the furnace than it is towards the rear, and as the result of this difference in thickness, and also because of 55 the large amount of volatile matter which is given off by the fuel near the front of the furnace, the gases arising at this point are usually somewhat deficient in oxygen. At the rear of the furnace the fuel bed is 60 comparatively thin and is composed largely of coke and ash. While the dampers 33 and 34 permit a reduction in the air pressure at this part of the furnace, nevertheless it has been found difficult in practical operation to burn 65 out all the combustible matter in the refuse

without at the same time bringing about a large excess of air in the rear of the chamber. In furnaces as heretofore utilized, this lean gas from the rear of the stoker has passed into the boiler tubes without becoming mixed with the rich gas from the front of the stoker. Such a method of operation has obviously resulted in great losses and inefficient combustion. This is particularly true in the case of an underfeed stoker, in which the combustion chamber ordinarily has vertical parallel walls and there are no arches or other provisions for causing the stratified gas columns to mix before entering the tubes. 70 75 80

In order to eliminate to a large extent this stratification of gases in the furnace and to bring about other advantages which will be apparent to those skilled in the art, I introduce a stream of pulverized fuel and air into the furnace chamber 10 and preferably directly thru the rear wall 12 thereof. For this purpose the rear wall 12, as illustrated, is provided with an opening 60, circular in shape and preferably flaring to an increased diameter on the furnace side. A horizontal cylindrical burner pipe 62 is mounted coaxial with the opening 60 and is provided with a substantially circular enlargement 63 at its outer end. The circular chamber 63 is provided with a tangential inlet 65 as shown clearly in Fig. 2. The pulverized fuel is brought to this inlet 65 from any suitable source and its tangential admission causes the fuel to whirl rapidly in the chamber 63 and become evenly distributed around the circumference of the pipe 62. 90 95 100

The pulverized fuel may be brought to the burner from a storage bin if desired, but I prefer to utilize a pulverizer 67 of the so-called unit type. If desired this pulverizer may be of the general type shown in the reissue patent to Blyth No. 16,229. The machine as illustrated comprises a coal hopper 68 and a discharge pipe 69 leading to the inlet 65. A suitable spreading device 72 is mounted adjacent to the discharge end of the burner pipe 62 and comprises a series of substantially radial vanes, each bent at an angle so as to whirl the issuing coal stream and throw it outwardly into the combustion chamber 10. 105 110 115

In some cases the so-called primary air which is used to bring the pulverized fuel to the burner may be insufficient for complete combustion and it may be desirable to introduce additional or secondary air thru the opening 60. I have therefore illustrated a series of guide vanes or louvers 75 arranged concentric with the pipe 62 as shown in Fig. 3. These louvers are arranged to give the secondary air a pronounced whirling motion preferably in the direction opposite to the pulverized fuel. In case it is desired to supply air to the louvers 75 under pressure I have shown a casing 76 arranged to form an air chamber around them. A fan 80 of any de- 120 125 130

sired construction may be connected to the air chamber by means of a duct 82 provided with a damper 83.

Having thus described my invention, the 5 operation and advantages thereof will be readily apparent to those skilled in the art. The hopper 16 is kept filled with fuel and the underfeed stoker is operated in substantially the same manner as it would be in an ordinary 10 furnace except that somewhat more air may be introduced to the overfeed grate section 30 and rocker apron 31 near the rear of the furnace in order to ensure the complete burning out of all the combustible matter in 15 the refuse. The hopper 68 is kept filled with fuel which passes into the pulverizer 67 where it is reduced to a fine powder. The pulverized fuel is then delivered thru the pipe 69 tangentially into the chamber 63 where it whirls around rapidly and is eventually 20 discharged as a turbulent blast into the chamber 10 thru the pipe 62, being whirled and thrown outwardly by the spreader 72 and thereby causing a thorough mixture of the 25 stratified gases arising from the stoker bed. Secondary air, if desired, may be supplied by the fan 80 and is whirled rapidly around the issuing coal stream by the louvers 75. The turbulent action of the pulverized fuel flame 30 in the combustion chamber 10 results in bringing about a thorough mixture of the rich gases from the front of the stoker with the lean gases from the rear thereof. In some 35 cases it may be desirable to operate the pulverized fuel burner with a deficiency of air by regulating the damper 83 in a suitable manner and to depend upon the excess air issuing from the rear portion of the stoker to make up for this deficiency and to provide 40 complete combustion. In case it is desired to operate the furnace at an extremely high rating it is unnecessary to force the stoker beyond its efficient capacity, for the pulverized fuel burner can be depended upon to 45 supply the extra fuel necessary.

A furnace operated in accordance with my invention will produce a great deal more heat in a given time than is possible with a furnace equipped with a stoker alone. This is 50 due to the fact that the available combustion space is utilized in a much more efficient manner than has heretofore been possible. The extra cost of the pulverizer and burner is 55 more than compensated for by the increased efficiency and capacity obtainable. In an ordinary pulverized fuel furnace the disposal of the ash is a serious problem. It is usually in a light, flocculent condition so that it is 60 easily blown away by the wind and hence it cannot be sold for filling material. In a furnace 65 constructed in accordance with my invention, however, the ash from the pulverized fuel flame falls on top of the fuel bed and is transported therewith to the clinker grinders 70 which easily dispose of it. The pulverized

fuel ash is so mixed with the ash from the underfeed stoker that no problem of disposal is presented. The pulverized fuel flame may be operated alone if desired by first protecting the metal parts of the stoker within the 70 furnace by a bed of ashes.

Having thus described my invention, what I claim as new and desire to secure by Letters Patent is:—

1. A furnace comprising walls defining a combustion chamber, a stoker having means for feeding a bed of fuel progressively from the front to the rear wall of the chamber and to an ash dump within the chamber and adjacent to the rear wall thereof, means for feeding a regulatable amount of air to the fuel bed and for providing an excess of air adjacent the ash dump to burn all of the combustible material from the ash, a fuel pulverizer, a burner pipe connected therewith and opening thru a wall of the combustion chamber, and means for regulating the amount of air to said burner pipe so that the air will be insufficient in amount to burn the pulverized fuel and a portion of the latter will be free to combine with the excess air from the stoker fuel bed, thereby equalizing the combustion throughout the combustion chamber and causing efficient burning of both types of fuel. 75

2. A furnace comprising walls defining a combustion chamber, an underfeed stoker in said chamber having retorts and tuyères for admitting air adjacent to the top surface of the fuel bed, means for feeding fuel lengthwise of said retorts towards an ash dump adjacent to the rear wall of the furnace, means for regulating the air supply to said tuyères so that an excess of air is provided adjacent the ash dump to ensure complete combustion of the fuel as it is moved rearwardly, a source of supply of pulverized fuel, a burner pipe adjacent to the rear end of the combustion chamber, and means for supplying air to said pulverized fuel in insufficient amount to cause complete combustion, said parts being so constructed and arranged that the pulverized fuel issuing into the combustion chamber will combine with some of the excess air passing through the 100 fuel bed of the underfeed stoker and thereby ensure efficient combustion of both types of fuel. 105

3. A furnace comprising walls defining a combustion chamber the rear wall of which is provided with an opening, an underfeed stoker therein having a plurality of parallel retorts extending rearwardly from the front wall of the chamber, an overfeed grate section in the rear of said retorts, an ash dump in the rear of the overfeed grate section and adjacent the rear wall of the chamber, means for feeding a bed of fuel through said retorts and along said overfeed 120 grate section to the ash dump, means for 125 transporting the fuel bed from the overfeed grate section to the ash dump, and means for 130

supplying air to the fuel in said retorts and on said overfeed grates, a pulverized fuel burner of the turbulent type mounted on said rear wall to deliver through said opening and means to supply air and pulverized fuel to said burner.

4. A furnace comprising walls defining a combustion chamber, an underfeed stoker in said chamber having a plurality of parallel retorts extending rearwardly from the front wall thereof, means within the combustion chamber forming an ash dump in the rear of the retorts, means for feeding fuel lengthwise of said retorts and towards the ash dump, means for supplying air to burn the fuel on the stoker, and means including a burner pipe extending through a wall of said chamber for projecting a blast of pulverized fuel and air into the combustion chamber over the fuel bed, thereby mixing the air and the combustible gases arising from the fuel bed.

5. A furnace comprising walls defining a combustion chamber, an underfeed stoker therein having a plurality of parallel retorts extending rearwardly from the front wall of the chamber, an ash dump in the rear of the retorts, means for feeding a bed of fuel through said retorts to the ash dump, means for supplying air to the fuel in said retorts, one wall of the chamber being provided with an opening, a pulverized fuel burner mounted on said wall and arranged to discharge through said opening, said burner and opening being so located that the flame is over the ash dump, and means to supply air and pulverized fuel to said burner for combustion.

Signed at Worcester, Massachusetts, this
10 23rd day of September 1927.

FRED H. DANIELS.
